Primary Examiner — April Rivas(74) *Attorney, Agent, or Firm* — Edward Podszus(57) **CLAIM**

The ornamental design for a lightweight heat sink, as shown and described.

DESCRIPTION

FIG. 1 is a top perspective view of the new design for a lightweight, heat sink as seen from the front, top;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof, the opposite side view being a mirror image thereof; and,

FIG. 7 is a bottom perspective view thereof.
